UNITED STATES PATENT OFFICE

RODNEY J. WOOD, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND

CREDIT FILE

Application filed January 12, 1923. Serial No. 612,182.

This invention relates generally to filing systems and has particular reference to filing cabinets for filing memoranda regarding transactions with customers in retail stores.

5 One object of the invention is to simplify the structure, as well as the means and mode of operation of such devices, whereby they will not only be cheapened in construction, but will be more efficient in use, capable of 10 being easily and rapidly operated, and unlikely to get out of repair.

Another object is to provide an improved file to which additional units may be added to increase the capacity of the file.

15 Another object is to provide a single set of filing units for both temporary and permanent filing in each file leaf by having a designating member separating the temporary filing from the permanent.

20 With these and incidental objects in view, the invention consists in certain novel features of construction and combinations of parts, the essential elements of which are set forth in appended claims and a preferred 25 form or embodiment of which is hereinafter described with reference to the drawings which accompany and form part of this specification.

Of said drawings:

30 Fig. 1 is a right side elevation of the filing device with the right hand side of the housing omitted.

Fig. 2 is a detail of a portion of the housing taken on the line 2—2 of Fig. 1.

35 Fig. 3 is a detail of a portion of the housing.

Fig. 4 is a section, partly broken away, taken on the line 4—4 of Fig. 1.

Fig. 5 is a front view of an index unit.

40 Fig. 6 is a detail end view of a portion of an index unit.

The improved device includes a number of pivoted units or sections normally accessible to the clerks, and provided with holders to receive charge, received on account and other memoranda as they are made out. These units comprise a plurality of leaves which serve as both temporary and permanent files.

45 At the end of the day, or any other desired period, the contents may be transferred from

the temporary position to the permanent position.

Each leaf is provided with a swinging arm, a portion of which is visible to the operator when all of the slips of that particular file are in the permanent position. But should there be one or more slips in the temporary position, in front of the arm, the arm will not be visible. This arrangement aids the operator in readily ascertaining, at any time, the slips that are to be changed from the temporary to the permanent position.

55 There are several ways in which the invention disclosed in this case might be used. One practical and efficient way in which it may be used, is as follows.

60 Considering the file unit disclosed in Fig. 4, let it be assumed that when the merchant comes to his place of business in the morning, all of the account slips for the various 65 customers, namely, "Swan," "Slick," etc., are filed behind the horizontally projecting indicating arms, in which conditions of the parts all of such indicating arms are clearly 70 visible to the merchant. Assume that customer "Slick" comes in the store and makes a purchase of several articles. The proprietor fills out an account slip, goes to his file, and taking hold of the left-hand leaf 55, the 75 one bearing the name "Swan," swings the same outwardly without raising the indicator arm associated with "Slick's" leaf, and places the slip in the space presented between the raised leaf and the horizontally projecting 80 indicator arm. He then allows the first leaf to assume its normal position, thus holding the account slip for customer "Slick" in the temporary filing position between the indicator arm and the preceding leaf.

85 Customer "Tiler" then comes in and makes a purchase, and the proprietor after filling out the slip, takes hold of the fourth leaf from the left-hand end, or in other words, the leaf bearing the name "Tyson," and raises the same, after which he places "Tiler's" slip 90 between the raised leaf and the horizontal indicator arm.

95 Let it be assumed that the next three customers to make purchases are "Tomy," "Umer," and "Uller." After making out the 100

slips for these customers he files them as he has filed the two preceding ones for "Slick" and "Tiler," that is, in front of the indicator arms associated with the leaves bearing the names of those customers.

5 Customer "Zahn" makes a purchase and the proprietor takes hold of the leaf bearing the name "Young," raises the same, and places the slip in front of the finger associated 10 with the "Zahn" leaf.

This procedure is followed all through the day, and in the evening when the merchant wishes to check up on the number of customers that have been in during the day, and 15 enter their accounts in his ledger, he can immediately ascertain how many there were, and who they were by looking at the file units, such as disclosed in Fig. 4. Due to the fact that the indicator arms for "Swan," 20 "Slim," "Tyson" and "Young" are visible, he knows that they have not made any purchases that day, and he can also ascertain that all of the customers that have slips placed in front of their associated indicator arms, have 25 made purchases during the day.

Now, when it comes to transferring his accounts into the ledger it is only necessary for him to take the slips that lie in front of the indicator fingers, because he knows that 30 amounts on those slips lying behind the indicator fingers have been previously posted, as the customers with whom those slips are associated made no purchases during the day. Therefore, he takes customer "Slick's" slip 35 and posts the figures thereon in the ledger, then taking hold of the left-hand leaf, or in other words, the one bearing the name "Swan," raises the same far enough to raise the index finger associated with "Slick's" leaf, away from the leaf bearing "Slick's" name, and files "Slick's" slip in the permanent filing section behind the finger and in front of "Slick's" leaf. He then takes "Tiler's" slip and posts it and raises the leaf 40 bearing the name "Tyson" far enough to raise the finger associated with "Tiler's" leaf away from such leaf, so that he can place "Tiler's" slip between "Tiler's" leaf and the horizontally projecting indicating arm.

45 He does this with all of the slips that show that the customers made purchases during the day, and his file is then ready for the next day's business, all of the indicator arms now being visible in front of the permanently filed 50 slips.

The device is so constructed that additional units may be added from time to time to increase the capacity of the file and take care of additional accounts.

55 An index to the accounts is carried on swinging units within the housing and is made accessible by lifting the top cover.

Describing the device in detail, the filing units are enclosed in a casing or housing 15.

60 The front of the casing consists of a door 16

(Fig. 1) attached to the main portion of the casing by a hinge 17. The top of the casing comprises a movable cover 18 with a flange 19 formed on the front end to overlap the front door 16. Formed on the right and left sides of the cover 18 are flanges 20 and 21 (Figs. 2 and 3) having elongated openings 22 into which project pins 23 and 24 carried by blocks 25 secured to the housing 15. A latch secured to the front door 16 is provided to normally secure the cover in place. This latch comprises a hinge 26, one portion of which is secured to the front door 16 while the other portion supports a rotatable knob 27 having on its lower end a button 28 which operates with a transversely extending elongated opening 30 in a cupped retaining disk 29 secured to the under side of the cover 18. By giving the knob member 27 a quarter turn in either direction from the position shown in Fig. 1, the latch may be opened to permit it to be disengaged from the cover which may then be raised at its forward end with the pins 23 and 24 (Fig. 4) as the pivots. The elongated openings 22 permit the cover to be moved to the rear of the casing into a position at right angles to the normal position, thus providing easy access to the files.

Secured to the casing near the right and left sides are two parallel filing unit supporting plates 36 and 37 (Fig. 1). The plate 36 is provided with a plurality of holes 38 while the plate 37 is provided with a plurality of holes 38 and slots 39. The holes and slots in these plates constitute pivot bearings for lugs 41 carried by filing units 40.

The last hole and slot near the rear ends of the plates 36 and 37 are located lower than adjacent holes and slots to render the file supported thereby easily distinguishable from the others, as it may be desirable to use this as a special file.

The number of units in a file varies according to the number of accounts. Referring to Fig. 1, there are eleven units shown, which represent the normal number for this size file. These units normally incline slightly toward the rear of the casing, resting against a rod 42 supported at each end in slotted plates 43 and 44 secured to the sides of the casing. As additional files are added, the rod 42 is moved to a new position in the slotted plates. A resilient clamping plate 45, secured at each end to the plate 37, normally retains the left hand lug 41 of the auxiliary units in the slots 39. When additional units are installed, this plate 45 is adapted to spring a sufficient amount to permit the lugs 41 to enter the slots 39. As shown in cross section in Fig. 4, the upper portion of the plate 45 is bent outwardly to the left, to cause this plate to spring away from the plate 37 upon being engaged by the left hand lug 41 of the filing unit as it is put in place. After the pivot lug passes off the bent over flange of the re-

70

105

110

115

120

125

130

silent clamping plate 45, said plate springs back to its normal position, thus holding the filing units in their operative positions. Flanges 46 (Fig. 1) formed on the filing units supporting plate 36 and 37, and extending at right angles thereto, are provided for the purpose of bracing these plates 36 and 37 against the sides of the casing.

The file units 40 are normally maintained in parallel relation to each other by brackets 47 and 48 (Fig. 4), secured near the top of each unit and near the right and left sides respectively. The brackets on one unit support the unit in front. Each unit has a right angle shelf 50 near the bottom, extending across its full width and upon which the memoranda rests when placed in the files.

Each unit 40 contains a plurality of overlapping file leaves 55 (Fig. 4) hinged on their left hand edges to the unit 40 by rods 56 supported by lugs 57 formed on the unit. A torsion spring 58 entwined about the rod 56 retains the leaf in normal position, as shown in Fig. 4. At their upper ends the leaves are formed with pockets 59 to receive cards 54 bearing identification data.

Mounted upon the rod 56 of each leaf hinge is an indicator arm 60 (Fig. 4) which extends horizontally across the leaf 55 with the right hand end exposed to view when the sales slips are in their permanent positions, which is back of this arm. In temporary filing of the slips they are placed in front of the arms 60, as shown by the second, fifth, sixth, seventh, eighth, and tenth slips in Fig. 4, so that when the time comes for placing the various slips in their permanent positions, they are readily detected as no arms appear in front of these slips. In other words, the visible horizontally disposed indicator arms 60 indicate to the proprietor, which of the customers have not made any purchases during the day, and tell him that he need pay no attention to those slips underlying the indicator arms 60 when it comes to posting the amounts in his ledger. The first slip on the left hand side is partially concealed by a cover leaf 61 similar in construction to the other leaves.

In gaining access to the various files, the front door 16 of the casing is moved forwardly on its pivot to permit a forward swinging movement of a cover 65 (Fig. 1) pivoted at its lower edge in the same manner as the file units. The forward movement of this cover is under the control of two links 66, connected at their forward ends to lugs 67 secured to said cover 65. These links 66 are provided with elongated openings 68 into which project screw studs 69 mounted in brackets 70 secured to the sides of the casing. With the cover 65 in its forward position the first file unit is exposed to view and is accessible for filing sales slips. The remaining units also may be rendered accessible

for filing sales slips by moving one or more file units forwardly until arrested by the cover 65 or their preceding unit.

An index to the various files enables the operator to readily locate a file. This index is in the form of cards 74 (Fig. 5) inserted in grooves formed in a plate 75 having pivot lugs 76 and 77. The lug 76 has a bearing in a round hole in a bracket 78 secured to the right side of the casing 15, and the lug 77 is pivoted in an angular slot, enlarged at the lower end, to form a bearing, in a bracket 79 secured to the left side of the casing 15. The lugs 76 and 77 are rectangular projections, similar to the lugs 41 (Fig. 1), and lie in the plane of the index plate 75. The cards contain the names of customers, alphabetically arranged, together with a number representing the position of the account in the file. For example, account "119" signifies that it is the ninth file in the eleventh unit, as shown in Fig. 4. Referring to Fig. 1, the index plates are shown in their normal positions, with the lower plate supported at its forward end on a rod 80 supported at each end in slots in the plates 43 and 44. This bottom plate 75 may be supported by any other suitable means. The upper index plate 75 normally lies on the lower plate. The index cards being on the under side of the plates, it is necessary to raise them to a vertical position when referring to the index, as shown in Fig. 5.

While the form of mechanism herein shown and described is admirably adapted to fulfill the objects primarily stated, it is to be understood that it is not intended to confine the invention to the one form or embodiment herein disclosed, for it is susceptible of embodiment in various forms, all coming within the scope of the claims which follow.

What is claimed is:—

1. In a filing device, a file unit, a plurality of vertically disposed overlapping leaves carried by the unit between which data sheets may be inserted, and a swinging member for each leaf, the indicator members each mounted to swing relatively to their respective leaves, behind which indicator members data sheets may be placed for permanent filing and in front of which indicator members data sheets may be placed for temporary filing the free ends of the indicator members extending beyond the free edges of the preceding leaves.

2. In a filing device, a plurality of file units, a plurality of overlapping swinging members attached to each file unit to retain sales slips, and swinging indicating means located behind certain of said swinging members to coact with and swing relatively to the next succeeding swinging member for separating temporarily filed sales slips from permanently filed slips.

3. In a filing device, a plurality of filing units; pivot lugs on said units; means com-

prising a supporting plate having open slots to support one lug of each unit; a resilient clamping member secured to said supporting plate and having its lower edge normally in position to contact the upper edges of said lugs, said clamping member being adapted to spring away from the supporting plate, and spring back to normal position; and an inclined flange on the clamping member adapted to be operated upon by the pivot lugs as the filing units are inserted, to spring the clamping member aside to permit the lugs to pass by it and into the slots in the supporting plate, after which the resilient member springs back and contacts the upper edges of the lugs to maintain the inserted filing units in operative positions.

4. In a filing device, the combination of a plurality of successively arranged swinging supporting members for retaining both permanently and temporarily filed slips, and an indicator associated with each member to distinguish the permanently filed slips each indicator mounted to swing relatively to its associated member from the temporarily filed slips.

5. In a filing device, the combination of a plurality of swinging members for retaining on their faces, both permanently and temporarily filed slips, an indicator associated with each swinging member to separate the permanently filed slips from the temporarily filed slips, and resilient means to press the swinging members against the indicators to maintain the indicators in their normal effective positions.

6. In a filing cabinet, the combination with a casing; filing units suitably hinged within the casing in a horizontal plane to swing towards and from the front of the cabinet; a series of overlapping filing leaves individually hinged at one vertical side to their respective filing units; and springs to yieldingly retain the overlapping leaves in their overlapping positions; of a spring-pressed indicator arm associated with each leaf and swinging on the same hinge therewith to contact with the next succeeding leaf.

7. In a filing cabinet, the combination with a casing; filing units suitably hinged within the casing in a horizontal plane to swing towards and from the front of the cabinet; a series of hinge members supported on and extending in spaced relation horizontally across the face of a filing unit; a series of overlapping spring-pressed filing leaves connected to the respective hinge members; and a spring-pressed indicator arm associated with each of the filing leaves to extend across the face of such leaf to a point beyond the free edge of the next preceding leaf.

8. In a filing cabinet, the combination with a casing; filing units suitably hinged within the casing in a horizontal plane to swing towards and from the front of the cabinet; a

series of hinge members supported on and extending in spaced relation horizontally across the face of a filing unit; a series of overlapping spring-pressed filing leaves connected to the respective hinge members; and a spring-pressed indicator arm connected, respectively, to the same hinge members as the filing leaves, each indicator arm extending across the face of its respective filing leaf.

9. In a filing cabinet, the combination with a casing; filing units suitably hinged within the casing in a horizontal plane to swing towards and from the front of the cabinet; a series of hinge members supported on and extending in spaced relation horizontally across the face of a filing unit; a series of overlapping spring-pressed filing leaves connected to the respective hinge members; spring-pressed indicator arms connected, respectively, to the same hinge members as the filing leaves, and extending across the face of each filing leaf, the indicator arms associated with certain of the filing leaves being connected to the hinge members for the next preceding filing leaves, respectively.

In testimony whereof I affix my signature.

RODNEY J. WOOD.
